[57] ABSTRACT

A cradle for supporting a plurality of articles such that the cradle and articles may be enclosed in a shrink film to form a package.

SHRINK FILM CRADLE

BACKGROUND OF THE INVENTION

1. Field of the Invention

The invention relates to package construction wherein a plurality of articles are held in a predetermined arrangement by a filmlike means, and more particularly to a cradle for supporting the articles.

2. Description of the Prior Art

It has become popular to package consumer goods in convenient-sized containers, such as cans, in clusters of four, six, or eight or more. Beverages and aerosol products are but two among many types of articles sold in clusters or groups of containers. A common packaging technique is that of providing a plastic or paperboard cradle for a plurality of articles and surrounding the cradle and articles with a plastic shrink film, usually transparent so that a purchaser may readily see and identify the product.

Inasmuch as such packages are utilized commercially in large numbers, any savings, however slight, in material required, or conservation of waste, or ease of manufacturing is reflected in significant savings to the manufacturer and ultimately to the consumer.

SUMMARY OF THE INVENTION

It is therefore an object of the invention to provide a new cradle for such packages, the cradle being of such design as to require a minimum of material, virtually eliminate waste, and simplify manufacturing of the cradle and construction of the entire package.

With the above and other objects in view, as will hereinafter appear, a feature of the present invention is the provision of a cradle member comprising an elongated rectangularly-shaped member, first and second portions thereof disposed at either end thereof being essentially U-shaped, each defined in part by a U-shaped slot, the two portions being adapted to be disposed substantially normal to a floor portion. When normal to the floor portion, the first and second portions are parallel and opposed to each other and form first and second walls upstanding from the floor portion, each wall comprising a top portion which is transverse to said member and supported by two leg portions joined to the floor portion.

The above and other features of the invention, including various novel details of construction and combinations of parts, will now be more particularly described with reference to the accompanying drawings and pointed out in the claims. It will be understood that the particular device embodying the invention is shown by way of illustration only and not as a limitation of the invention. The principles and features of this invention may be employed in various and numerous embodiments without departing from the scope of the invention.

BRIEF DESCRIPTION OF THE DRAWINGS

Reference is made to the accompanying drawings in which is shown an illustrative embodiment of the invention from which its novel features and advantages will be apparent.

In the drawings:

FIG. 1 is a plan view of a blank from which is made one form of cradle illustrative of an embodiment of the invention;

FIG. 2 is a perspective view showing the blank of FIG. 1 being transformed into a cradle; FIG. 3 shows the completed cradle; and FIG. 4 illustrates the cradle in use as part of a shrink film package for a plurality of consumer articles.

DESCRIPTION OF THE PREFERRED EMBODIMENT

Referring to FIG. 1, it will be seen that the cradle is made from an elongated rectangularly-shaped member 2. The member 2 is preferably of paperboard and includes a first portion 4 disposed at one end of the member 2. The first portion 4 is essentially U-shaped and is defined in part by a first U-shaped slot 6 in the member 2. The portion 4 is adapted to be bent (FIG. 2) along a fold line 8 to a position substantially normal to a floor portion 10 of the member 2 (FIG. 3).

The member 2 further includes a second portion 12 (FIG. 1) at the other end of the member 2. The second portion 12 is also essentially U-shaped and is defined in part by a second U-shaped slot 14 in the member 2. The portion 12 is adapted to be bent (FIG. 2) along a fold line 16 to a position substantially normal to the floor portion 10 (FIG. 3).

Referring to FIG. 3, it will be seen that when the first and second portions 4, 12 are bent so as to be substantially normal to the floor portion 10, the portions 4, 12 are substantially parallel to each other and are in opposed positions. The first portion 4 thereby forms a wall 20 upstanding from the floor portion 10 and comprising a top portion 22 disposed transversely of the member 2 and supported by two leg portions 24, 26 joined to the floor portion 10. In like manner, the second portion 12 thereby forms a wall 30 upstanding from the floor portion 10 and comprising a top portion 32 disposed transversely of the member 2 and supported by two leg portions 34, 36 joined to the floor portion 10.

Thus, there is provided a unitary cradle member having a floor on which may rest a plurality of articles and two upstanding walls forming three zones on the working surface of the floor and acting as buffers between those zones. Material required is held to a minimum and waste is virtually eliminated inasmuch as nothing is cut out and discarded except for the cutting of the slots 6, 14. Only two simple folding movements are required to place the cradle in condition for receiving articles, thus manufacturing is relatively non-complex.

In operation, the cradle is cut and folded to the position shown in FIG. 3, whereupon the cradle receives a plurality of articles A. The articles and cradle are then exposed to a shrink film covering process by which a film F is disposed about the cradle and articles, as shown in FIG. 4, to complete the package.

It is to be understood that the present invention is by no means limited to the particular construction herein disclosed and/or shown in the drawings, but also comprises any modifications or equivalents within the scope of the disclosure. For example, if desired, a separate additional divider (not shown) may be placed lengthwise on the cradle, or transverse to the walls 20, 30 to provide six zones instead of three and, further, provide a separate compartment for each article.

Having thus described my invention what I claim as new and desire to secure by Letters Patent of the United States is:

1. A package comprising:

- a. a cradle for supporting a plurality of rows of articles, said cradle having a floor portion and a pair of upstanding wall portions,
- b. said floor portion including a central portion between said wall portions supporting a central row containing at least one article thereon,
- c. said floor portion further including a pair of outer floor portions extending outwardly from said wall portions providing a pair of outer rows supporting at least one article each thereon, said outer floor portions being narrower than said central portion wherein at least a portion of the at least one article

- in each outer row overhangs an edge of said outer floor portion, and
  - d. wrapping means substantially surrounding said cradle and the articles thereon.
- 5   2. A package as defined in claim 1 wherein said wall portions are U-shaped and said floor and wall portions are integrally formed from a single piece of stock material.
- 10   3. A package as defined in claim 2 wherein said stock material is paperboard.
